 corporation of Alabama

Application September 3, 1936, Serial No. 99,283

8 Claims. (Cl. 66—172)

This invention relates to a rib knit fabric and particularly a circular knit fabric as produced on a multi-feed circular rib knitting machine. The invention more particularly concerns a fabric, of the type noted, having a rubber strand laid in relatively spaced courses of the stitches of which the fabric is composed.

One object of the present invention is to produce a design on the outside of a circular knit ribbed fabric of the type above noted, partly by the main knitting threads fed to the needles at the various feeds respectively, and partly by supplemental threads plated over said main threads on predetermined stitch wales and which will coordinate with said main threads to form the design and provide a fabric especially adapted for use as the tops of children's hosiery, etc.

Other features of the invention and the construction of the fabric in detail will be fully disclosed hereinafter, reference being had to the accompanying drawings, of which:

Fig. 1 diagrammatically illustrates a child's sock with a figured rib top made in accordance with the present invention; and

Fig. 2 diagrammatically illustrates the stitch formation of the fabric of the stocking top shown in Fig. 1.

The present invention more especially relates to the knitting of a ribbed top on a small diameter circular rib knitting machine which normally is provided with but two feeds and wherein each feed includes two main yarn thread feeding fingers and means for selectively wrapping predetermined needles with supplemental threads to form vertical, i. e. walewise stripes, and means for selectively operating the two main yarn feeding fingers, for changing the yarn in the foundation fabric to produce horizontal, i. e. coursewise, stripes.

Machines capable of producing fabric in the above noted manner are quite old and well known in the art. Due to the small diameter of the needle cylinders, in such machines, it has been thought to be necessary to limit the machines to two feeds, in order to accommodate the necessary cams and other mechanism for operating the needles, for selecting the needles to be wrapped, and for changing the main knitting yarn when desired.

With machines of the above type no means has heretofore been provided for laying a rubber strand in the stitch courses.

The rate of production of machines of the above noted type is limited to two courses for each complete cycle of relative circular move-

ment between the needle cylinder and dial and the cams which operate the cylinder and dial needles.

The present case is predicated upon the application of a third feed to the normally two feed machine above noted, said third feed being of simple construction, without yarn change or needle wrapping, and including a finger for laying a rubber thread into the course of stitches produced at and by the additional third feed; whereby the production rate of the machine is increased fifty per cent and whereby it is possible to lay a rubber thread in every third course of stitches, without sacrificing yarn changing or needle wrapping at the two original feeds.

In a fabric produced on a machine modified as above noted one thread is constantly fed from the additional feed and knit to form every third course of stitches throughout the length of the fabric, the two original feeds respectively producing the two intermediate courses.

In cases where continuous needle wrapping to form vertical stripes has occurred at one or both of the original feeds, in the two intermediate courses, the plating effected by such needle wrapping will be interrupted at the third course produced by the additional feed, leaving blank spots in the plating.

One object of the present invention is to so arrange and select the plating threads with respect to the constant thread of the third feed that no blank spots will appear in the design, as would be caused by non-wrapping at the third feed as above noted.

The drawings show a stocking top A composed of successive stitch course series or repeats A¹, A², A³, etc., each series containing, in the present instance, three stitch courses 1, 2, 3. The thread a of course 1 of each series is constant as to color and kind throughout the length of the fabric, being fed by the additional or supplemental feed of the machine as above noted; the thread b of course 2 of each series is variable as to kind and/or color, being fed by one or the other of the two yarn fingers at one of the normal or original feeds of the machine; and the thread c of course 3 of each series is likewise variable as to kind and/or color in the various course series or repeats throughout the length of the fabric.

The top A includes outside or cylinder wales 4 alternating, in the present case, with inside or dial wales 5.

Relatively spaced outside wales 4, in the courses 2 and 3 of each course series are plated with

supplemental threads 6 and 7 respectively. These threads normally lie in front of the body or main threads *a* and *b* in said wales, in the courses 2 and 3. In the courses 1, due to the fact that no needle wrapping mechanism is located at the supplemental feed, the plating threads 6 and 7 pass to the back of the fabric and float walewise thereof across each of the courses 1, 1, as indicated at 8 and 9 respectively, 10 which normally would form a blank spot in the design on the face of the fabric.

In order to prevent such blank spots the main or body thread *a*, fed to the needles by the supplemental feed, is preferably of a kind and color 15 corresponding to the kind and color of one of the plating or wrapping threads and in the present case is shown as corresponding to the plating thread 6, hence the spot 8 at which this thread passes to the back of the fabric, instead of being blank and showing an interruption in the plating on the wale 4, is closed by a body stitch 20 10 composed of the main or body knitting thread *a*, which as noted is of the same kind and color as the plating thread 6.

25 In cases where the second plating thread 7 is the same color and kind as the plating thread 6, the design produced would be in the form of blocks, the centers of which would be composed of foundation yarns *b* and *c* which would be of 30 a color or colors differing from the color of the foundation yarn *a* and plating threads 6 and 7, and fed by the two normal feeds of the machine in courses 2 and 3 respectively, while the horizontal lines defining the tops and bottoms of 35 the blocks would be formed by the foundation yarn *a* fed by the additional feed in the course 1, the vertical lines defining or depicting the sides of the blocks being formed by the plating threads 6 and 7 of the same color as the body 40 thread *a*.

In cases where the plating threads 6 and 7 are of different colors, with one being the same color as the body thread *a* and the other being of a different color and also different from either of 45 the body threads *b* and *c* in all or in the majority of the course series A¹, A², A³, etc., or where one of the body threads *b* or *c* is changed in predetermined relatively spaced series A¹, A², A³, etc., to agree in color with the plating thread 7, the 50 effect obtained is that of a plaid.

In Fig. 2 the body thread *b* in course 2 in one of the course series is shown as being of the same kind and color as the plating thread 7, as indicated at 2b, to produce the plaid effect shown 55 in Fig. 1.

The upper end of the top A is provided with a welt B which is constructed in the same manner as the top A, i. e. in course series or repeats of courses 1, 2 and 3 composed of body or foundation thread *a*, *b*, *c* respectively.

The lower edge of the top A is knit, sewn, looped, or otherwise secured to the leg portion C of the stocking.

In order to make the sock or stocking self-65 supporting a rubber thread 11 is laid in each of the courses 1 of each course series A¹, A², A³, etc., or in predetermined course series only, as desired, thus spacing the strands 11 and providing sufficient elasticity to enable the top to yield 70 freely without uncomfortably binding but at the same time to cling firmly to the limb of the wearer.

The rubber strands 11 are held in the fabric between the front wales 4 and back wales 5 with-75 out being knit into the courses 1 in which the

rubber strands are laid, although, if and when desired the rubber feeding finger may be set or operated to feed the rubber thread 11 to the needles with the body yarn *a* to knit-in the rubber with the body yarn *a* or in the welt B, at or adjacent the line of connection between the top A and the leg C, and or at desired places within the top A intermediate the welt B and leg C to keep the rubber from being pulled out at its ends and from slipping through the courses 1.

10

15

Obviously, the stocking top A shown in Fig. 1 could be made on a regular three feed machine when making large size stocking tops and wherein the machines are of sufficiently large diameter to permit of the use of three normal feeds each 15 provided with yarn changing mechanism including multiple yarn feeding fingers and needle wrapping means and a rubber inlay attachment at one of the feeds, or by using one feeding finger at one feed as a rubber inlaying or rubber knitting-in finger and by using the needle wrapping means at the other two feeds only.

20

I claim:

1. A circular knit ribbed fabric comprising longitudinal inside and outside stitch wales and transverse stitch courses arranged in series each containing a plurality of courses composed of separate threads respectively, with a corresponding course in each series constantly composed of one yarn of predetermined color throughout the 30 length of the fabric and the remaining courses of each series composed of yarns which are changeable in the respective course series throughout the length of the fabric and with predetermined laterally spaced wales in the remaining courses 35 of each series respectively plated with threads of a color similar to that of said one course, said plating threads passing behind the stitches of said one course at the intersections of said one course with said plated wales, forming a design 40 sign on the outside of said fabric.

30

2. A circular knit ribbed fabric comprising longitudinal inside and outside stitch wales and transverse stitch courses arranged in series each containing a plurality of courses composed of 45 separate threads respectively, with a corresponding course in each series constantly composed of one yarn of predetermined color throughout the length of the fabric and the remaining courses of each series composed of yarns which are changeable in the respective course series throughout the length of the fabric and with predetermined laterally spaced wales in the remaining courses of each series respectively plated with threads of a color similar to that of said one course, said 50 plating threads passing behind the stitches of said one course at the intersections of said one course with said plated wales, forming a design 55 sign on the outside of said fabric and an elastic thread laid in said one course in a plurality of said series 60 successively, between said inside and outside wales.

50

55

3. A circular knit ribbed fabric comprising longitudinal inside and outside stitch wales and transverse stitch courses arranged in series each containing a plurality of courses composed of separate threads respectively, with a corresponding course in each series constantly composed of one yarn of predetermined color throughout the 65 length of the fabric and the remaining courses of each series composed of yarns which are changeable in the respective course series throughout the length of the fabric and with predetermined laterally spaced wales in the remaining courses of each 70 series respectively plated with threads of a color 75

65

60

65

70

75

similar to that of said one course, said plating threads passing behind the stitches of said one course at the intersections of said one course with said plated wales, forming the outlines of design 5 on the outside of said fabric, said remaining courses in said series being composed of selectively variable colors different from the color of said outlines, to form the body of said designs within said outlines,

10 4. A circular knit ribbed fabric comprising longitudinal inside and outside stitch wales and transverse stitch courses arranged in series each containing a plurality of courses composed of separate threads respectively, with a corresponding 15 course in each series constantly composed of one yarn of predetermined color throughout the length of the fabric and with predetermined laterally spaced wales in the remaining courses of each series respectively plated with threads of a color 20 similar to that of said one course, said plating threads passing behind the stitches of said one course at the intersections of said one course with said plated wales, forming the outlines of design 25 on the outside of said fabric, said remaining courses in said series being composed of selectively variable colors different from the color of said outlines, to form the body of said designs within said outlines and an elastic thread laid in said one course in a plurality of said series successively, between said inside and outside wales.

5. A circular knit ribbed fabric comprising longitudinal inside and outside stitch wales and transverse stitch courses arranged in series each containing a plurality of courses composed of 35 separate threads respectively, with a corresponding course in each series constantly composed of one yarn of predetermined color throughout the length of the fabric and with predetermined laterally spaced wales in the remaining courses of each 40 series respectively plated with threads of a color similar to that of said one course, said plating threads passing behind the stitches of said one course at the intersections of said one course with said plated wales, and one of said remaining 45 courses in each of a number of relatively spaced course series being formed respectively of a thread different in color from that of said one course, forming a transverse stripe in each of said spaced course series.

50 6. A circular knit ribbed fabric comprising longitudinal inside and outside stitch wales and transverse stitch courses arranged in series each containing a plurality of courses composed of 55 separate threads respectively, with a corresponding course in each series constantly composed of one yarn of predetermined color throughout the length of the fabric and with predetermined laterally spaced wales in the remaining courses of each series respectively plated with threads of a color similar to that of said one course, said plating threads passing behind the stitches of said one course at the intersections of said one course with said plated wales, and one of said remaining

courses in each of a number of relatively spaced course series being formed respectively of a thread different in color from that of said one course, and predetermined outside wales lying intermediate said plated wales being plated with threads 5 of a color similar to that of the last said courses and together with the first said courses and the first said plated wales forming a plaid design on the outside of said fabric.

7. A circular knit ribbed fabric comprising 10 longitudinal inside and outside stitch wales and transverse stitch courses arranged in series each containing a plurality of courses composed of separate threads respectively, with a corresponding 15 course in each series constantly composed of one yarn of predetermined color throughout the length of the fabric and with predetermined laterally spaced wales in the remaining courses of each series respectively plated with threads of a color similar to that of said one course, said 20 plating threads passing behind the stitches of said one course at the intersections of said one course with said plated wales, and one of said remaining courses in each of a number of relatively 25 spaced course series being formed respectively of a thread different in color from that of said one course, and predetermined outside wales lying intermediate said plated wales being plated with threads 30 of a color similar to that of the last said courses and together with the first said courses and the first said plated wales forming a plaid design on the outside of said fabric, and an elastic thread laid in said one course in a plurality of said series successively, between said 35 inside and outside wales.

8. A circular knit ribbed fabric comprising longitudinal inside and outside stitch wales and transverse stitch courses arranged in series each containing a plurality of courses composed of 40 separate threads respectively, with a corresponding course in each series constantly composed of one yarn of predetermined color throughout the length of the fabric and with predetermined laterally spaced wales in the remaining courses 45 of each series respectively plated with threads of a color similar to that of said one course, said plating threads passing behind the stitches of said one course at the intersections of said one course with said plated wales, and one of said 50 remaining courses in each of a number of relatively spaced course series being formed respectively of a thread different in color from that of said one course, and predetermined outside wales lying intermediate said plated wales being plated with threads 55 of a color similar to that of the last said courses and together with the first said plated wales forming a plaid design on the outside of said fabric, the residue of said remaining courses being composed of threads of selectively variable colors 60 to form a background for said plaid design.

ROBERT E. DAVIS.
